UNITED STATES PATENT OFFICE.

KARL VON DREGER, OF BERLIN, GERMANY.

STARTING DEVICE FOR ELECTROMOTORS.

No. 923,157.

Specification of Letters Patent.

Patented June 1, 1909.

Application filed May 23, 1908. Serial No. 434,458.

To all whom it may concern:

Be it known that I, KARL VON DREGER, a citizen of the Empire of Germany, residing at Berlin, in the Empire of Germany, have invented a new and useful Starting Device for Electromotors, of which the following is a specification.

There are known starting devices for electromotors comprising a lever riding over the waved circumference of a segment or the like, which latter carries two contact springs and is elastically connected with the operating handle by means of a spiral spring. For starting the electromotor the operating handle is then turned in one direction and the lever serves for braking the segment or the like, so as to prevent it from following too rapidly the operating handle, so that the two contact springs may successively pass over various contact pieces arranged in two concentric arcs, and for stopping the electromotor the operating handle requires to be turned back to its initial position. Such starting devices present two serious defects. One defect is, that the two contact springs also lag behind the operating handle during the switching-off operation, which under circumstances may create serious disturbances. The other defect is, that the resistance offered to the lever by the waved circumference of the segment or the like does not decrease in proportion to the diminishing tension of the strained spiral spring on the segment or the like with the two contact springs following the operating handle after the latter has been turned forward for starting the electromotor.

My invention relates to improvements in such starting devices for electromotors, whereby the said two defects are avoided.

Instead of the segment or the like I employ a ring loose on the periphery of a drum which is elastically connected with the operating handle by means of a spiral spring and I provide the ring on its outside with waved surfaces and notches. A lever is provided which is adapted to ride with its free end over the waved surfaces of the ring during the forward turn of the operating handle and to engage in the notches of the ring for stopping same during the return of the operating handle. Means are provided for coupling the ring with the drum during the forward turn and for disconnecting the former from the latter during the return. The operating handle is adapted to at once take

along with it during its return the drum with the two contact levers. Thus the first defect named above is avoided. The waves in the waved surfaces of the ring are made irregular in such a manner, that in each series of waves the first wave is made the shortest and highest and the last wave is made the longest and lowest, while the intermediate waves successively decrease in height and increase in length. Then the braking effect of the lever upon the ring will decrease in about the same proportion as the tension of the spiral spring diminishes. Thus the second defect named above is avoided.

I will now proceed to describe my invention with reference to the accompanying drawing, in which—

Figure 1 is a section through a starting device on the line *c—d* in Fig. 2, when looked at in the direction of the arrows, and Fig. 2 is another section through the same on the line *a—b* in Fig. 1, when looked at in the direction of the arrows. Fig. 3 is a view similar to Fig. 2, showing a slightly modified construction.

Similar characters of reference refer to similar parts in all the views.

In a casing or box 1 of any known construction a shaft 8 is provided, which may form a part of any known device not shown. This shaft 8 extends through a cover 30 of the box 1 and carries without a loose operating handle 23 and within a loose spring-drum 6 and a loose lever 20. The lever 20 is shown as provided with two claws 25 which engage in corresponding recesses in the nave of the operating handle 23. Thereby the lever 20 is obliged to partake in the movement of the operating lever 23. On the periphery of the drum 6 a ring 9 is mounted to turn, while it is prevented from axially shifting by a collar 6' and an internally screw-threaded ring 31 or the like. In the race of the ring 9 there is provided a recess 11 (see Fig. 2) in the periphery of the drum 6, and in this recess 11 a pawl 10 is mounted to rock on a suitable pin shown, while a leaf spring 12 serves for pressing the pawl 10 on the inner circumference of the ring 9. The latter is provided with three notches 13, into any of which the pawl 10 can engage. A spiral spring 19 is provided within the drum 6 and is attached with its internal end to the nave of the lever 20 and with its external end to the inside of the drum 6, as is shown. The rim of the drum 6 is provided with a projection 24 on which the

lever 20 normally rests under the action of a slight tension in the spring 19. The periphery of the ring 9 is provided with three series of waves 17 and three notches 14⁰, 14¹, 14² which latter are set at an angle of 120° from one another. The first wave in each series 17 (when counting from any of the notches 14⁰, 14¹, 14² in a direction opposite to that of the hands of a clock) is made the shortest and 10 the highest, while the following waves successively decrease in height and increase in length, as is clearly shown in Fig. 2. In the casing 1 a pin 15 is provided, on which a lever 14 is mounted to rock. The hooked free 15 end of this lever 14 is adapted to ride over the waved periphery of the ring 9. Between the lever 14 and the inside of the casing 1 a helical spring 16 is inserted, which serves for pressing the hooked end of the lever 14 on the ring 9. The tension of the helical spring 16 can be regulated by means of an adjusting screw 32 in the lever 14. On the side of the drum 6 and insulated therefrom are fastened two contact springs 4 and 5, which are electrically connected with one another. Sufficient play is left to the three 20 parts 6, 20 and 23, which can longitudinally shift on the shaft 8 and are normally pressed together against a collar 33 on the shaft 8 by 25 the two contact springs 4 and 5.

On the inside of the casing 1 and insulated therefrom are fastened for example a contact strip 2, six contact pieces 3, 3¹ and two insulating pieces 27, all of which are disposed in 30 two concentric rows around the shaft 8 and are well known. The contact spring 4 is adapted to slide over one insulating piece 27 and the contact strip 2, while the other contact spring 5 is adapted to slide over the 35 other insulating piece 27 and the series of contact pieces 3, 3¹ and to strike against a projection 28 of the last contact piece 3¹, whereby the turn of the drum 6 with the two contact springs 4 and 5 in the direction of 40 the arrow 18 is limited. The angle through which the two contact springs 4 and 5 can be turned from their normal position shown in full lines in Fig. 2 to their other extreme position over the last contact piece 3¹ 45 amounts to 120° like the angle between any two of the notches 14⁰, 14¹, 14² in the ring 9. The operating handle 23 normally occupies the same position as the two contact springs 50 4 and 5, which position is indicated by the dotted center line A—8, and can be turned beyond the last contact piece 3¹ to the other extreme position indicated by the dotted center line B—8. In this extreme position the operating handle 23 may be held by hand, 55 it bearing against some pin provided on the cover 30, or it may be secured by means of any known stopping, pinching or locking device.

The starting device operates as follows: 60 For the normal position of the operating handle 23 in the dotted center line A—8 in

Fig. 2 the hooked end of the lever 14 engages in any of the three notches 14⁰ (as shown), 14¹, 14² and the pawl 10 engages in the corresponding notch 13 of the ring 9. When the operator is desirous of starting the electro-motor, he turns the operating handle 23 in the direction of the arrow 18 to the other extreme position B—8 with any speed he likes. Thereby of course the lever 20 is moved off from the projection 24 of the drum 6 and the spiral spring 19 is strained, so that its tension will pull the drum 6 with the two contact springs 4 and 5 forward in the direction of the arrow 18, and the pawl 10 will take the ring 9 along with it, but the spring-pressed lever 14 will brake the ring 9 and prevent it together with the drum 6 and the two contact springs 4 and 5 from following too rapidly the operating lever 23. During this movement the tension of the spiral spring 19 will diminish, but as the waves 17 also decrease in height and increase in length, the diminishing tension of the spiral spring 19 will be still able to overcome the friction of the hooked end of the lever 14 on the periphery 80 of the ring 9 and to move the contact springs 4, 5 to their extreme position in which one of them (5) strikes the projection 28 of the last contact piece 3¹. In this manner the two contact springs 4 and 5 are moved forward 85 with a nearly uniform speed. The small tension still remaining in the spiral spring 19 will suffice for pressing the contact spring 5 against the projection 28 and thus securing the two contact springs in their extreme 90 position, while the hooked end of the spring-pressed lever 14 engages in the following notch 14¹ of the ring 9. Of course the lever 20 will be at a small distance from the projection 24. In this manner the electromotor 95 is gradually started in spite of any rapidity in the movement of the operating handle 23. When the operator wants to stop the electromotor, he turns the operating handle 23 back from the position B—8 to the initial position A—8 with any speed he likes. The lever 20 striking the projection 24 will thereby take along with it the drum 6 and the pawl 10 will slide on the inner circumference of the ring 9 until it engages in the following notch 110 13. Thus the two contact springs 4 and 5 are moved back as rapidly as the operating handle 23, as it should be. The ring 9 is of course prevented from returning by the hooked end of the lever 14 engaging its 115 notch 14¹.

The starting device described may be varied in many respects without departing from the spirit of my invention. For example the lever 14 may be weighted instead 125 of spring-pressed. The ring 9 may be provided on its side with a waved groove, as is indicated in Fig. 3, it having on its inside nearer the shaft 8 substantially the same outline as the waved periphery of the ring 9 130

shown and described above with reference to Fig. 2. The free end of the lever 14 may have a pin or a pin with a roller for engaging in the waved groove. In this case the lever 5 14 is preferably not spring-pressed or weighted but is pivotally connected with the rod 34 of a piston fitting loosely in the cylinder 29 of an air-brake or liquid-brake of a known construction, as is indicated in Fig. 3.

10 I claim:

1. In a starting device for electromotors, the combination with an operating handle, of a drum, a spring connecting said operating handle with said drum for pulling the latter 15 forward, a ring turnable on said drum, means for connecting said ring with said drum during the forward turn of said operating handle for switching-on, means for stopping said ring during the return of said operating handle for switching-off, contact pieces, two electrically connected contact springs on said drum and insulated therefrom and adapted to slide over said contact pieces, and means for braking said ring with a force decreasing 20 in proportion to the diminishing tension of said spring so as to move said two contact springs with a nearly uniform speed, said operating handle being adapted during its return to take along with it said drum with 25 said two contact springs.

2. In a starting device for electromotors, the combination with an operating handle, of a drum provided with a recess and a projection, a spring connecting said operating 35 handle with said drum for pulling the latter forward, a ring turnable on said drum and provided with a notch, a spring-pressed pawl in the recess of said drum and adapted to engage in the notch of said ring for taking the 40 latter along with it during the forward turn of said operating handle for switching-on, means for stopping said ring during the return of said operating handle for switching-off, contact pieces, two electrically connected 45 contact springs on said drum and insulated therefrom and adapted to slide over said contact pieces, and means for braking said ring with a force decreasing in proportion to the diminishing tension of said spring so as 50 to move said two contact springs with a nearly uniform speed, said operating handle being adapted during its return to strike the projection of said drum and thereby take along with it the latter with said two contact 55 springs.

3. In a starting device for electromotors, the combination with an operating handle, of a drum provided with a recess and a projection, a spring connecting said operating 60 handle with said drum for pulling the latter forward, a ring turnable on said drum and provided on its inner circumference with a notch and on its outside with a waved surface and a notch, a spring-pressed pawl in the 65 recess of said drum and adapted to engage

in the internal notch of said ring for taking the latter along with it during the forward turn of said operating handle for switching-on, a support, a lever mounted on said support to rock and adapted to ride with its free 70 end over the waved surface of said ring and to engage the external notch of same for preventing it from returning during switching-off, contact pieces, two electrically connected contact springs on said drum and insulated therefrom and adapted to slide over said contact pieces, and means for braking said ring by means of said lever, the waves in the waved surface of said ring successively decreasing in height and increasing in length 80 for reducing the friction of said lever in proportion to the diminishing tension of said spring so as to move said two contact springs with a nearly uniform speed, and said operating handle being adapted during its return 85 to strike the projection of said drum and thereby take along with it the latter with said two contact springs.

4. In a starting device for electromotors, the combination with a plate, of a shaft at 90 right angles to said plate, an operating handle on said shaft, a drum loose on said shaft, a spring connecting said operating handle with said drum for pulling the latter forward, a ring turnable on said drum, means 95 for connecting said ring with said drum during the forward turn of said operating handle for switching-on, means for stopping said ring during the return of said operating handle for switching-off, contact pieces on said 100 plate, two electrically connected contact springs on said drum and insulated therefrom and adapted to slide over said contact pieces, and means for braking said ring with a force decreasing in proportion to the diminishing tension of said spring so as to move 105 said two contact springs with a nearly uniform speed, said operating handle being adapted during its return to take along with it said drum with said two contact springs. 110

5. In a starting device for electromotors, the combination with a plate, of a shaft at right angles to said plate, an operating handle on said shaft, a drum loose on said shaft and provided with a recess and a projection, 115 a spring connecting said operating handle with said drum for pulling the latter forward, a ring turnable on said drum and provided with a notch, a spring-pressed pawl in the recess of said drum and adapted to engage in the notch of said ring for taking the latter along with it during the forward turn of said operating handle for switching-on, means for stopping said ring during the return of said operating handle for switching-off, contact 120 pieces on said plate, two electrically connected contact springs on said drum and insulated therefrom and adapted to slide over said contact pieces, and means for braking said ring with a force decreasing in proportion 125

tion to the diminishing tension of said spring so as to move said two contact springs with a nearly uniform speed, said operating handle being adapted during its return to strike the 5 projection of said drum and thereby take along with it the latter with said two contact springs.

6. In a starting device for electromotors, the combination with a plate, of a shaft at 10 right angles to said plate, an operating handle on said shaft, a drum loose on said shaft and provided with a recess and a projection, a spring connecting said operating handle with said drum for pulling the latter forward, 15 a ring turnable on said drum and provided on its inner circumference with a notch and on its outside with a waved surface and a notch, a spring-pressed pawl in the recess of said drum and adapted to engage in the internal 20 notch of said ring for taking the latter along with it during the forward turn of said operating handle for switching-on, a lever mounted on said plate to rock and adapted to ride with its free end over the waved surface of said ring and to engage the external notch of same 25 for preventing it from returning during switching-off, contact pieces on said plate, two electrically connected contact springs on said drum and insulated therefrom and adapted to slide over said contact pieces, and means for braking said ring with a force decreasing in proportion to the diminishing tension of said spiral spring so as to move said two contact 30 springs with a nearly uniform speed, said operating handle being adapted during its return to strike the projection of said drum and thereby take along with it the latter with said two contact springs.

7. In a starting device for electromotors, the combination with a plate, of a shaft at right angles to said plate, an operating handle on said shaft, a drum loose on said shaft, a spiral spring connecting said operating handle with said drum for pulling the latter forward, a ring turnable on said drum, means for connecting said ring with said drum during the forward turn of said operating handle for switching-on, means for stopping said ring during the return of said operating handle for switching-off, contact pieces on said plate, two electrically connected contact springs on said drum and insulated therefrom and adapted to slide over said contact pieces, and means for braking said ring with a force decreasing in proportion to the diminishing tension of said spiral spring so as to move said two contact springs with a nearly uniform speed, said operating handle being adapted during its return to take along with it said drum with said two contact springs.

8. In a starting device for electromotors, 65 the combination with a plate, of a shaft at

right angles to said plate, an operating handle on said shaft, a drum loose on said shaft and provided with a recess and a projection, a spiral spring connecting said operating handle with said drum for pulling the latter 70 forward, a ring turnable on said drum and provided with a notch, a spring-pressed pawl in the recess of said drum and adapted to engage in the notch of said ring for taking the latter along with it during the forward turn 75 of said operating handle for switching-on, means for stopping said ring during the return of said operating handle for switching-off, contact pieces on said plate, two electrically connected contact springs on said drum and insulated therefrom and adapted to slide over said contact pieces, and means for braking said ring with a force decreasing in proportion to the diminishing tension of said spiral spring so as to move said two contact 80 springs with a nearly uniform speed, said operating handle being adapted during its return to strike the projection of said drum and thereby take along with it the latter with said two contact springs.

9. In a starting device for electromotors, the combination with a plate, of a shaft at right angles to said plate, an operating handle on said shaft, a drum loose on said shaft and provided with a recess and a projection, a spiral spring connecting said operating handle with said drum for pulling the latter forward, a ring turnable on said drum and provided on its inner circumference with a notch and on its outside with a waved surface and a notch, a spring-pressed pawl in the recess of said drum and adapted to engage in the internal notch of said ring for taking the latter along with it during the forward turn of said operating handle for 90 switching-on, a lever mounted on said plate to rock and adapted to ride with its free end over the waved surface of said ring and to engage the external notch of same for preventing it from returning during switching-off, contact pieces on said plate, two electrically connected contact springs on said drum and insulated therefrom and adapted to slide over said contact pieces, and means for braking said ring by means of said lever, the waves in the waved surface of said ring successively decreasing in height and increasing in length for reducing the friction of said lever in proportion to the diminishing tension of said spiral spring so as to move said 100 two contact springs with a nearly uniform speed, and said operating handle being adapted during its return to strike the projection of said drum and thereby take along with it the latter with said two contact 105 springs.
